INVENTOR

Lucien S. Crandall

UNITED STATES PATENT OFFICE.

LUCIEN S. CRANDALL, OF NEW YORK, N. Y.

DESIGN FOR AN INDICATOR-FRAME.

SPECIFICATION forming part of Design No. 24,140, dated March 19, 1895.

Application filed February 20, 1895. Serial No. 539,132. Term of patent 14 years.

To all whom it may concern:

Be it known that I, LUCIEN S. CRANDALL, a citizen of the United States, residing at New York, county and State of New York, have invented and produced a new and original Design for Indicator-Frames, of which the following is a full, clear, and exact description, reference being had to the accompanying drawing, which shows the frame in front elevation.

The leading and characteristic features of my design are the frame A, rectangular in outline; the bar extensions B; and the central bars C. The upper and lower bars *a*, *b*, of the frame A, are slightly curved. The bar exten-

sions B, radiate from the four corners of the frame A, and the bars C, are so arranged, within the outline of the frame-bars, as to have the form of a conventionalized cross.

D, are figures, circular in outline, disposed along the respective bars.

E, is a supporting stand for the frame.

I claim—

The design for an indicator frame as herein described, and shown in the accompanying drawing.

LUCIEN S. CRANDALL.
